LATE NEWS DEVICE

Filed Aug. 4, 1923

UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

LATE NEWS DEVICE

Application filed August 4, 1923. Serial No. 655,774.

This invention relates to a curved stereotype printing plate having a cavity therein in which type, slugs or plates for news or illustrations can be inserted. Although described as a late news device and intended to be used principally for that purpose, it is, of course, capable of use for inserting matter at any time and for any purpose.

The principal object of the invention is to provide a plate with the cavity so arranged that the plate itself will hold the type, slugs or plates for illustrations without the need for any other chase or turtle.

Reference is to be had to the accompanying drawings, in which

Fig. 1 is a perspective view of a curved stereotype printing plate constructed in accordance with this invention, showing one late news cavity empty and another filled with printing matter;

Fig. 2 is a rear elevation of the plate on an enlarged scale showing slugs in position in the cavity, some of them broken away to show the construction of the plate;

Fig. 3 is a sectional view on the line 3—3 of Fig. 2;

Fig. 4 is a sectional view on the line 4—4 of Fig. 2 and also showing the position of the plate on the cylinder;

Fig. 5 is a perspective view of one of the printing slugs, and

Fig. 6 is a perspective view of the locking means therefor.

The invention is shown as applied to a curved printing plate 20 provided with integral characters on its convex face and having one or more cavities 21 therein. Each of these cavities is preferably smaller on the printing or convex side of the plate. In this case ledges are shown which constrict the cavity on the printing side of the plate for that purpose. The ledges are shown as being discontinued for a short distance at 24 to allow for the insertion of matter.

A cavity shaped in this way is intended to be used with slugs 25 of type or any other like printing units. These slugs or other printing units are made with printing surfaces 26 in the usual manner and with projecting ends 27. These projecting ends are of such di-

mensions as to fit under the ledges 22 at both ends and permit the printing surfaces to come up flush with the printing surface of the plate. The slugs can be inserted from the front through the openings 24 and slid along under the ledges. Then a locking device comprising two bars 30 and 31 held apart by springs 32 is inserted through the openings 24 and held in position by the ledges 22 including the small detached portion thereof at two opposite corners of the opening in the plate.

I have shown the invention as applied to a curved plate in which the slugs are adapted to rest at the concave side of said plate back against the printing cylinder 33 on which the plate is mounted. In this way the plate and cylinder hold the slugs in position against lateral displacement and there is no need of employing any separate chase or turtle to hold them. The plate itself is the chase. The opposite straight surfaces 29 of the cavity may be made parallel or substantially so, so that the core which is used to form the cavity can be easily removed from the plate. The cavity however need not go completely through the plate but may go but part way, the inserted slugs or type resting at the back upon the bottom of the plate cavity itself.

Although I have illustrated and described only a single form of the invention I am aware of the fact that modifications can be made therein by any person skilled in the art without departing from the scope of the invention as expressed in the claims. Therefore, I do not wish to be limited to all the details of construction herein shown and described but what I do claim is:—

1. As an article of manufacture, a stereotype printing plate having a cavity for late news slugs, said cavity having opposite parallel recesses on the rear side and ledges in front of them, whereby slugs with ends depressed below the printing surface can be inserted behind said ledges, said ledges having a pair of opposite openings all the way through them near one end through which the slugs and a locking means therefor can be inserted from the front.

2. As an article of manufacture, a stereo-

type printing plate having a cavity there-through for late news slugs, said opening having opposite parallel recesses on the rear side and ledges in front of them, whereby slugs with ends depressed below the printing surface can be inserted behind said ledges and held between the plate and its supporting device on the press, said ledges having a pair of opposite openings all the way through them near one end through which the slugs and a locking means therefor can be inserted from the front.

3. As an article of manufacture, a stereotype printing plate having a cavity there-through for late news slugs, said cavity having opposite parallel ledges, whereby slugs with ends depressed below the printing surface can be inserted behind said ledges and held between the plate and its supporting device on the press, said ledges having an opening through them for receiving a locking means.

4. As an article of manufacture, a stereotype printing plate having a cavity for late news slugs, said cavity having opposite ledges, whereby slugs with ends depressed below the printing surface can be inserted behind said ledges, said ledges having a pair of opposite openings through them through which the slugs and a locking means therefor can be inserted from the front.

In testimony whereof I have hereunto affixed my signature.

HENRY A. WISE WOOD.
